UNITED STATES PATENT OFFICE.

JOHN G. BERGQUIST, OF CHICAGO, ILLINOIS, ASSIGNOR TO AMERICAN SINTERING COMPANY, OF CHICAGO, ILLINOIS, A CORPORATION OF ILLINOIS.

APPARATUS FOR SINTERING FINE ORE.

No. 853,433.

Specification of Letters Patent.

Patented May 14, 1907.

Application filed December 21, 1905. Renewed October 19, 1906. Serial No. 839,701.

To all whom it may concern:

Be it known that I, JOHN G. BERGQUIST, a citizen of the United States, residing at Chicago, in the county of Cook and State of Illinois, have invented certain new and useful Improvements in Apparatus for Sintering Fine Ore, of which the following is a specification.

This invention relates to improvements in apparatus for sintering fine ore, and among the salient objects of the invention are to provide an apparatus adapted for continuously carrying out the process of sintering ore, the ore being fed into one end of the furnace 5 and discharged at the other; to provide in such an apparatus means for regularly dislodging from the interior of the furnace by mechanical means the fused and semi-fused material which tends to adhere to the walls 10 of the furnace; to provide for the purpose last mentioned a continuously moving and endless scraper mechanism, the scraping member of which alternately passes through the furnace and a cooling medium outside of 15 the furnace; to provide in a furnace of the general character referred to, a construction which enables ready access to be had to the interior both of that portion in which the preliminary step or steps of the process is 20 carried out and in that portion in which the actual fusing is accomplished, without interrupting the operation of the apparatus; to provide in such a furnace a construction which enables either pulverized or fluid fuel 25 to be used and introduced continuously; to provide an improved construction and arrangement of the auxiliary mechanism whereby the material to be acted upon and the treated material is continuously delivered to 30 40 and removed from the furnace; to provide improvements in details of construction and arrangement contributing to facility of inspection and repair; and in general to provide an improved apparatus of the character referred to.

To the above ends the invention consists in the matters hereinafter described and more particularly pointed out in the appended claims.

The invention will be readily understood from the following description, reference being had to the accompanying drawings, in which—

Figure 1 is a general view in side elevation,

certain parts being shown in section, of an apparatus constituting a preferred embodiment of the invention; Fig. 2 is a transverse sectional view taken on line 2—2 of Fig. 1 and looking in the direction of the arrows; Fig. 3 is a longitudinal axial section through the lower delivery end of the furnace body and the wheeled removable closure which closes the latter; Figs. 4, 5 and 6 details of the scraper chain.

An apparatus embodying my invention is adapted for use for sintering either flue dust derived from blast furnaces or for sintering fine iron ore having the same general characteristics as flue dust. It has been found in practice that such ores can be sintered, i. e. 65 agglomerated, into lumps of a size suitable for charging into a blast furnace and retaining their form until smelted, by passing a stream of such ore gradually and continuously through a furnace in which the ore 70 is tumbled as it fuses in such manner as to bring about proper agglomeration. Heretofore it has been found impractical to carry out such a process continuously for any considerable length of time by reason of the fused 75 ore adhering to and fouling the interior of the smelting portion of the furnace to such an extent as to render the same practically inoperative. The conditions incident to carrying out such a process have rendered it 80 practically impossible to keep the interior of the furnace clean by stoking and it has been found necessary to interrupt the operation of sintering at more or less frequent intervals 85 and remove the clinker and slag manually; 90 this being an exceedingly difficult operation and injurious to the lining of the furnace. In the apparatus described these difficulties have been overcome.

Referring to the drawings, 1 and 1' designate suitable foundations upon which are mounted suitable roller supports or cradle mechanism, designated as a whole 2 and 2', respectively, adapted to receive and support two tubular furnace body sections, 3 and 4, 100 respectively. Both furnace sections are inclined somewhat from the horizontal, and the longer, receiving end section is elevated and offset with relation to the other section so that convenient access may be had to the 105 interior of both sections through their proximate ends. The delivery end of the receiving section and the receiving end of the

lower section extend within a suitable housing 5 forming a complete inclosure of the proximate ends of the furnace body sections, except that the rear wall of this housing is omitted from the lower side of the upper section downwardly, as seen clearly in Fig. 2. A removable closure 6 in the front side of the upper part of the housing affords access to the delivery end of the upper section 4.

10 In order to conduct the material passing through the upper section, to the lower section, and at the same time to form a partition which in conjunction with the upper part of the housing 5 forms a substantially closed passage leading from one furnace section to the other, an inclined chute board 7 is provided, which is pivotally mounted upon a transverse horizontal pivot shaft 8 extending through the side walls of the 15 housing at a point just below and intermediate the length of the chute board. The width of the chute board corresponds approximately to the internal width of the chamber 5, its upper end when in normal position resting against the lower edge of the rear wall of the housing and through which the upper furnace section enters, and its lower end is provided with a narrowed extension 9 which extends a short distance within the receiving end of the lower furnace section. Just in rear of the lower end of the chute board and just outside of the receiving end of the lower furnace section is built up a removable closure 10, preferably formed of 20 fire brick, so that the chute board in conjunction with the said removable closure 10 completely partitions the interior of the housing and thus forms a closed passage above the chute board leading from one furnace section to the other. The chute board is provided upon its upper side with a covering of refractory material, and along one edge of the board this refractory covering is built up or thickened to form a guard wall 7' 25 which serves to deflect the ore flowing over the chute board toward the opposite side of the lower receiving section. Both sections of the furnace are rotated bodily so as to continuously tumble the ore and thus effect 30 the feeding of the latter through the furnace sections. To this end each section, in addition to its supporting rings 11 and 11' is provided with a gear ring, as 12 and 12', which is engaged and driven by a suitable train of 35 gear mechanism, designated as a whole 13 and 13', respectively. In the particular instance illustrated, the two furnace sections are shown as actuated from the same source of power and arranged to rotate at about the same speed, but they may be independently driven and rotated at different speeds if preferred or found desirable. In any event the rate of rotation is comparatively slow.

40 The receiving end of the upper section 4 terminates in a chamber formed in the base

portion 14 of a stack or chimney. Through a suitable opening in the side of the chamber referred to is arranged to extend a feed chute 15 which is arranged to deliver at its lower end into the receiving end of the furnace section. A suitable elevator mechanism designated as a whole 16 lifts the ore from a suitable boot or hopper 17 and discharges it into the receiving end of the chute 15; it being understood that the rate of feed to the furnace will be regulated by means of this elevating apparatus. 70

The delivery end of the lower section projects within a chambered closure, designated as a whole 18; this closure being constructed 80 to completely surround the terminal end of the furnace and being provided at its lower side with a delivery opening 19 through which the ore is discharged. The interior of the closure 18 is lined with refractory material as well as the interiors of the two furnace sections and of the housing 5, as shown clearly in the sectional views. For convenience of removal the structure 18 is mounted 85 on wheels. 90

Describing now the mechanical scraper mechanism, 20 designates an endless chain or cable which is trained around suitable guide pulleys or sheaves, as 21, 22, 23 and 24, and also around a drive pulley 25, in such 95 manner that its upper lap extends through the interior of the lower furnace section 3 while its lower lap extends within a trough 26 which is kept supplied with cooling water. The guide pulleys 21 and 22 are so disposed 100 as to guide the upper lap of the chain in longitudinal contact with the interior of the furnace at a point far enough above the lower center line of the furnace body to be out of the way of the body of ore passing therethrough; but nevertheless well below the upper boundary of the lower half of the furnace, so that the weight of the chain will aid in maintaining the latter in wiping or dragging engagement with the inner surface of the 105 furnace body. Suitable apertures 27 and 28 are formed through the removable closures 10 and 18, respectively, for the passage of the chain therethrough. The chain 20 is provided at frequent intervals with scrapers 110 20', which may be conveniently cast upon the respective links which support them; these scrapers in their most approved form being disk-shaped, concave at their front side and beveled at their peripheries so as to 115 form continuous circular scraping edges 20''. 120

The drive sprocket 25 is shown as actuated by means of a pair of bevel gears 29 and 30; the latter being mounted on a shaft carrying a sprocket wheel 31 which is driven by a 125 sprocket chain leading to any suitable source of power. In order to enhance the scraping effect of the chain upon the interior of the furnace, the drive sprocket is mounted at the rear end of the furnace section and accord- 130

ingly draws upon the lower lap of the chain, thus insuring that whatever slack is in the chain will occur in the upper lap and accordingly permit the chain to rest with its full weight against the furnace wall. It is to be noted that the continuous rotation of the furnace body during the time the chain is likewise moving continuously therethrough, imparts a rotary or twisting movement to the chain, and this is a feature of advantage in that it insures the continual presentation of fresh or unclogged edges of the scraper disks to the furnace wall. Moreover it insures that these disks will wear uniformly and maintain their circular shape.

In the particular construction illustrated, I have shown the furnace as equipped with mechanism for introducing pulverized coal as a fuel. This fuel is introduced by means of a blast and to this end a blower 32 is provided near the delivery end of the furnace, with the delivery side of which communicates a blast pipe 33 which leads to and enters through an aperture in the closure housing 18, located about axially of the furnace body. A suitable hopper 34 is arranged to deliver a regulated quantity of fuel to the blower through a pipe 35; the feed opening being regulated by a slide valve 36 in said pipe.

The operation of the apparatus has been largely described in connection with the description of the mechanism. It may, however, be briefly recapitulated as follows: The apparatus being in operation, the furnace sections rotating slowly and the blower injecting a suitable supply of fuel which burns within the furnace sections, ore is fed gradually and continuously into the upper end of the upper section and by the rotation of the latter is fed steadily therethrough and delivered onto the chute board 7. By the latter the ore is conveyed to the lower section and progresses through the latter in the same manner, being gradually raised in temperature until it partially fuses within the lower section and the steady rotation of the latter has the effect of agglomerating the ore into lumps. Meantime the scraper chain continuously wipes the interior of the lower furnace section, and in this connection it is to be noted that the lower furnace section is rotated in such direction as to tend to carry the ore away from the chain. That is to say, the chain is located near the bottom of the descending side of the furnace. The clinker scraped from the interior of the furnace is chilled as soon as it encounters the water in the trough through which the lower lap of the chain travels, and this cooling together with the agitation effected by the travel of the chain through the trough, effectually dislodges the clinker from the scraper disks. I have found in practice that the apparatus may be operated continuously for any desired

length of time without interruption and without becoming in any wise impaired in its operation. It will be understood, of course, that the products of combustion pass through both furnace sections and escape through the stack. Whenever it becomes necessary to inspect or repair either of the furnace sections, this is readily accomplished; access to the upper section being had through the removable closure or door 6 and access to the lower section by removing the closure 18 or tilting the chute board 7 downwardly upon its pivot. Inasmuch as the most intense heat and fusing action occurs within the lower section, the latter requires inspection and repair more often than the upper, and the arrangement of the apparatus enables this to be accomplished conveniently.

It will, of course, be understood that the invention is not by any means confined to the exact construction and arrangement shown.

I claim as my invention:

1. In a sintering furnace apparatus, the combination of an upper tubular furnace body section movably supported to rotate upon its longitudinal axis and inclined from the horizontal, a lower furnace body section having its receiving end arranged in proximity to, but offset below, the delivery end of the upper section and also movably mounted to rotate about its longitudinal axis and inclined from the horizontal, an upright housing within the upper part of which the delivery end of the upper section extends and within the lower part of which the receiving end of the lower section extends, a removable closure in the wall of said housing opposite the delivery end of the upper section and through which access to the latter may be had, and an inclined movable chute board extending across the interior of said housing from a point below the delivery end of the upper section to the lower side of the receiving section, and an opening in said housing opposite the receiving end of the lower section, through which access to the latter may be had when the chute board is moved.

2. In a sintering furnace apparatus, the combination with a tubular furnace body section, movably supported to rotate upon its longitudinal axis, of a traveling scraper mechanism arranged to traverse the interior of the furnace in bearing with the inner surface thereof.

3. In an apparatus for treating minerals, the combination with a movable furnace body, the interior of which is subject to adhesion thereto of the material treated, of a traveling scraper mechanism arranged to traverse the interior of the furnace and moving at an angle to the direction of movement of the furnace body whereby the combined movement of said parts effects a progressive scraping of the furnace interior.

4. In an apparatus for treating minerals,

- the combination with a rotatable furnace body, the interior of which is subject to adhesion thereto of the material treated, of a traveling scraper mechanism arranged to traverse the interior of the furnace and moving at an angle to the direction of movement of the furnace body whereby the combined movement of said parts effects a progressive scraping of the furnace interior.
5. In an apparatus for treating minerals, the combination of a tubular rotatable furnace body, means for effecting the progressive travel therethrough of mineral to be treated, and a traveling scraper mechanism arranged to act upon the interior of said furnace and the scraper members of which move alternately into and out of the furnace, and means for actuating the same.
15. 6. In an apparatus for treating minerals, the combination with a movable furnace body provided at opposite ends with openings, of an endless scraper mechanism arranged to travel through said furnace body as to one of its laps and to travel around the outside of the furnace as to its other lap, whereby it is continuously cooled as to its outer part and heated by passing through the furnace.
25. 7. In an apparatus for treating minerals, the combination with a tubular rotatable furnace body, of an endless traveling scraper arranged to extend through said furnace body in bearing with the interior of the latter, and means for actuating the scraper mechanism and for rotating the furnace body.
30. 8. In an apparatus for treating minerals, the combination with a tubular internally circular furnace body mounted to rotate upon its longitudinal axis, of an endless
- scraper chain or cable mounted to travel through said furnace body and carrying a series of scrapers acting upon the interior of the furnace body, and mechanism for simultaneously rotating the furnace and continuously moving said scraper mechanism.
45. 9. In combination with a rotatable furnace body of tubular form, an endless scraper mechanism arranged to travel through said furnace body as to one of its laps and outside of the furnace as to its other lap, and means for subjecting the outer lap of the scraper mechanism to the action of a liquid cooling medium.
50. 10. In combination with a rotatable furnace body of tubular form, an endless scraper mechanism arranged to travel through said furnace body as to one of its laps and outside of the furnace as to its other lap, and a liquid receptacle through which said outer lap is arranged to travel.
55. 11. In an apparatus for treating minerals, the combination with a tubular rotatable furnace body, of an endless scraper mechanism arranged to travel through said furnace body consisting of a chain or cable and circular scrapers provided with peripheral scraping edges mounted at intervals apart upon said chain or cable and acting upon the interior of said furnace body, and means for simultaneously actuating the scraper mechanism and furnace body, whereby the interior of the furnace is progressively scraped and the scraper chain or cable is rotated upon its own axis by the engagement of the scrapers with the furnace wall.
65. 70. 75. JOHN G. BERGQUIST.
